(57) **CLAIM**

The ornamental design for a stroller frame, as shown and described.

DESCRIPTION

1. Stroller frame

1.1 is a front and left side perspective view of a stroller frame in accordance with the present invention;

1.2 is a rear elevational view of the stroller frame of 1.1;

1.3 is a bottom plan view of the stroller frame of 1.1;

1.4 is a front elevational view of the stroller frame of 1.1;

1.5 is a left side elevational view of the stroller frame of 1.1;

1.6 is a right side elevational view of the stroller frame of 1.1; and

1.7 is a top plan view of the stroller frame of 1.1.

The broken lines in the reproductions/drawings illustrate portions of the stroller frame that form no part of the claimed design.
